UNITED STATES PATENT OFFICE.

ELLSWORTH TILDEN, OF ASOTIN, WASHINGTON.

STUMP-BURNER.

1,160,012.

Specification of Letters Patent.

Patented Nov. 9, 1915.

Application filed September 2, 1914. Serial No. 859,869.

To all whom it may concern:

Be it known that I, ELLSWORTH TILDEN, a citizen of the United States, residing at Asotin, in the county of Asotin and State of Washington, have invented certain new and useful Improvements in Stump-Burners; and I do hereby declare the following to be a full, clear, and exact description of the invention, such as will enable others skilled 10 in the art to which it appertains to make and use the same.

This invention relates to new and useful improvements in stump burners and has for its principal object to provide a device which 15 will effectively direct flame of fire against a stump to destroy the same.

Another object of the invention is to provide a portable device which may be easily and quickly attached to a stump to perform 20 the above function, and which may be easily and quickly transported and set up for use.

With these and other objects in view, the invention consists in the combination and arrangement of parts which will be fully 25 set forth in the following specification and in the accompanying drawing, in which:

Figure 1 is a sectional view of a stump showing this improved stump burner as it would appear when applied thereto. Fig. 30 2 is a rear view in elevation of the stump burner, and Fig. 3 is a sectional view taken on line 3—3 of Fig. 1.

Referring now to the drawings by characters of reference, the numeral 1 designates 35 the stump which is first prepared by drilling or boring the hole 2 therein, a suitable smoke conveying pipe 3 is inserted in one end of the hole and carries at its opposite terminal the elbow 4 which is arranged to 40 communicate with the pipe 5 which is upturned to cause the proper draft through the stump.

Cooperating with the mechanism hereinbefore referred to is the fire box designated 45 as an entirety by the numeral 6 which comprises the cylindrical body 7 having formed at one end the closure 8 which is formed with the outlet aperture 9. A suitable smoke pipe 10 is secured to the end wall 8 and arranged to register with the outlet opening 9, and this pipe 10 has secured thereto the short length of pipe 11 carrying the flange 12 which is arranged to be inserted in the stump in such a manner that the flange 12 50 will limit the inward movement of the pipe. The end wall 13 of the burner 6 is pro-

vided with the fuel door 14 having formed thereon the draft controlling device 15, by means of which the amount of air permitted to enter the burner is controlled. A suitable partition wall 16 is secured within the cylindrical body 7 near the opening 9, and this wall is cut-away at its upper edge as at 17 to permit the hot gases from the interior of the cylindrical body 7 to pass into the 65 pipe 9 and from thence into the stump.

It will be apparent from the foregoing, that in use the stump is drilled as illustrated in the drawing and the short length 11 of pipe is then inserted in the aperture 70 as shown. The pipe 10 is then connected to the pipe 11, and it will thus be seen that communication will be formed between the burner 6 and the aperture 2 in the stump. The opposite terminal of the aperture has 75 pressed thereto the pipe 3 which is constructed so that it communicates with the pipe 5 and thereby creates a draft through the burner 6 and stump 1, thereby drawing the fire and the heat from the burner into 80 the stump and destroying the same. The device is then ready to be set in operation, and it will be apparent that the heat and fire from the burner will be drawn through the stump, thereby causing the same to be 85 completely demolished.

While in the foregoing there has been shown and described the preferred embodiment of this invention, it is to be understood that such changes in the combination and 90 arrangement of parts as may fall within the scope of the claims may be resorted to without departing from the spirit and scope of the invention.

Having thus described the invention, what 95 is claimed as new, is:—

1. A stump burner furnace comprising a cylindrical body adapted to receive inflammable material, a front wall secured to the body having a draft opening, a rear wall 100 secured to the body and provided with an outlet aperture, a partition wall secured within the lower part of the said body at a spaced interval from and extending to a point above the outlet aperture to prevent 105 the said inflammable material from clogging the outlet aperture, a pipe secured to said outlet aperture to direct the flame and gas from the body into a stump which is to be burned.

2. The combination with a stump having been previously prepared by drilling an

aperture therethrough, of a furnace, said furnace comprising a body adapted to receive inflammable material, a front wall secured to the body, said front wall being provided with a draft opening, a rear wall secured to the body, said rear wall being provided with an outlet aperture, a partition wall secured within the lower part of said body at a spaced interval from and extending to a point above said outlet aperture to prevent the inflammable material from clogging said outlet aperture, a pipe connected to said outlet aperture, the oppo-

site end of said pipe extending into the aperture in the stump and a draft pipe extending into the opposite end of the aperture in the stump, said draft pipe being arranged to cause a draft through the stump to draw the fire from the furnace into the stump thereby destroying the same. 15 20

In testimony whereof I affix my signature in presence of two witnesses.

ELLSWORTH TILDEN.
